UNITED STATES PATENT OFFICE.

JAMES CUMMINGS AND HAROLD ANDREW McGREGOR WILSON, OF SYDNEY, NEW SOUTH WALES, AUSTRALIA.

CINEMATOGRAPH MACHINE.

Application filed July 27, 1923. Serial No. 654,133.

To all whom it may concern:

Be it known that JAMES CUMMINGS and HAROLD ANDREW McGREGOR WILSON, subjects of the King of Great Britain and Ireland, residing at 29 Alberta Street, Sydney, in the State of New South Wales, Commonwealth of Australia, have invented certain new and useful Improvements in Cinematograph Machines, of which the following is a specification.

This invention relates to cinematograph machines and more particularly relates to the operating mechanism of such machines.

In the type of machine at present in use the gear controlling the movement of the film and the fan is complicated and costly consisting of many gear wheels and pinions and shafts allowing extensive wear and thus increasing the cost of maintenance. Also, the method of attaching the intermittent pinion to its shaft does not permit of ready removal and replacement except by experts.

Now the object of this invention is to provide a simple and efficient driving and controlling gear for the purpose of (a) driving the film actuating mechanism, (b) masking the film and (c) synchronizing the fan.

A further object of the invention is to provide a simple means of attaching the intermittent sprocket to its shaft so that it may be easily removed for replacement.

Further objects are to provide a driving and controlling mechanism which shall be inexpensive both in first cost and maintenance and which shall be silent in operation.

The invention refers to the type of machine in which the lamp housing, the light condenser, the lens and the gate are all rigidly mounted and the film control gear is adjustably mounted and in which the fan shaft is mounted to one side of the lens.

The invention will be now fully explained by referring to the accompanying drawings in which:—

Figure 1 is a perspective view of one side of the frame carrying the driving and controlling mechanism showing the fan synchronizing gear,

Figure 2 is a perspective view of part of the opposite side of the frame showing the means for masking the film.

Figure 3 is a part sectional elevation of the intermittent sprocket showing method of mounting same, and

Figure 4 is a perspective view of part of the intermittent sprocket.

The frame 5 to which the lens and the gate, both of which are not shown in the drawings, are attached is mounted in any well known manner on the machine. A plate 6 is slidably mounted within the frame 5 and is retained therein by the lugs 7. The machine shown in the drawings is adapted to be driven by an electric motor and the drive therefrom is taken by the pulley 8 mounted on the shaft 9 which passes through the plate 6 and transfers the drive to the cam gear, contained within the casing 10, actuating the intermittent sprocket 11.

A pinion 12 attached to the shaft 9 meshes with the wheel 13 which is mounted on a shaft 14 which, passing through the plate 6 carries the lower film sprocket 15. The upper film sprocket 16 is carried on the shaft 17 and is driven from the shaft 14 through the chain 18 engaging the chain sprockets 19 and 20 on the shafts 14 and 17.

The fan is attached to the shaft 21 mounted in bearings 22 and 23 and carrying the helical worm 24. The bearings are rigidly attached to a member 25 which is slidably attached to the plate 6 by the T-piece 26 which passes through the slot 27 therein.

The end of the member 25 is inclined and is kept bearing against a roller 28 attached to the frame 5 by the spring 29.

The intermittent sprocket 11 has two slots 30 formed in its barrel 31 which has a centrally situated integral collar 32, and is attached to its operating shaft 33 by means of a screw 34 in the collar 32 passing through a hole in the shaft.

When it is desired to mask the film the plate 6 together with all the film control gear and that part of the film between the upper and lower film sprockets 16 and 15 is moved vertically by turning the shaft 35 which, by means of the crank 36 and link 37 connecting with the projection 38 on the sliding plate 6, causes the film to alter its position relative to the aperture in the gate which is fixed so that each individual picture on the film when stationary registers with the aperture. The motion of the plate 6 is assisted by the helper springs 39.

The vertical movement of the plate 6 causes the member 25 to move in or out under the action of the roller 28 or the spring 110

29. This horizontal motion of the helical worm 24 for the reason that it is in mesh with the gear wheel 13 causes it together with the shaft 21 and the fan to be displaced angularly so that the fan is synchronized simultaneously with the masking of the film.

When the frame 5 is mounted in its place on the complete cinematograph machine the 10 operating mechanism is all contained within a suitable cover.

We claim:

1. A cinematograph operating mechanism in which the fan shaft is mounted in bearings adapted to be displaced horizontally on 15 a vertical plate by the relative movement between said vertical plate and a frame, and means for effecting the horizontal displacement of said bearings and shaft.

29. 2. A cinematograph machine operating mechanism in which the mechanism is mounted on a vertical plate adapted to rise and fall within a frame the fan shaft being supported in bearings mounted on a base attached to said vertical plate in such a manner as to allow of horizontal displacement, said base having an inclined end adapted to bear against a roller mounted on said frame, a spring on said frame adapted to 35 maintain said base in contact with said roller, a helical worm on said fan shaft adapted to mesh with a gear wheel and means for driving said gear wheel.

3. The improved cinematograph machine 35 operating mechanism comprising a vertical plate adapted to slide vertically in a frame,

said frame carrying the lens and gate, means for raising and lowering said plate, a driving shaft passing through said plate to the intermittent sprocket actuating gear, said 40 intermittent sprocket having a slotted barrel with a centrally disposed integral collar thereon and adapted to receive therein a screw passing through the intermittent 45 sprocket shaft, a pinion on said intermittent sprocket shaft adapted to engage with a gear wheel mounted on the shaft carrying the lower film sprocket, a helical worm mounted 50 on the fan shaft and engaging said gear wheel, the fan shaft bearings being mounted 55 on a base plate attached to and adapted to slide horizontally on said movable vertical plate, said base plate having an inclined end adapted to register with a roller attached to said frame, a spring adapted to 60 keep said base plate up to said roller, an upper film sprocket shaft passing through said sliding plate and adapted to be driven from said lower film sprocket shaft by a chain engaging chain sprockets on said upper 65 and lower film sprocket shafts, means for releasing said sliding vertical plate from said frame, and means for moving the vertical plate.

In testimony whereof they have affixed 65 their signatures in presence of two witnesses.

JAMES CUMMINGS.

HAROLD ANDREW McGREGOR WILSON.
